ATTORNEY.

UNITED STATES PATENT OFFICE.

FREDRICK EDWARD KAMPMAYER, OF PITTSBURG, PENNSYLVANIA.

DESIGN FOR A FEED-BAG SUPPORT.

SPECIFICATION forming part of Design No. 32,748, dated May 29, 1900.

Application filed April 26, 1900. Serial No. 14,509. Term of patent 7 years.

To all whom it may concern:

Be it known that I, FREDRICK EDWARD KAMPMAYER, a citizen of the United States of America, residing at 451 Ceeder street, Pittsburgh, in the county of Allegheny and State of Pennsylvania, have invented and produced a new and original Design for a Feed-Bag Support; and I do hereby declare the following to be a full, clear, and exact description thereof, reference being had to the accompanying drawing, which forms a part of this specification.

This invention relates to a new and useful design for a feed-bag support.

As shown in the accompanying drawing, the leading or material feature of my design consists of a single piece of wire rod bent at its middle to form a circular loop 1. The rod

is then twisted at 2 and the ends bent outwardly and thence downwardly to form legs 20 or shanks 3. These legs or shanks are spread farther apart at their ends than at the point near the twist, and each terminates in a spiral coil 4.

Having described my invention, what I claim as new, and desire to secure by Letters Patent, is—

The design for a feed-bag support, as herein shown and described.

In testimony whereof I have hereunto affixed my signature in the presence of two subscribing witnesses.

FREDRICK EDWARD KAMPMAYER.

Witnesses:

RICHARD S. HARRISON,
JAS. J. McAFFEE.
